1.5 : Top

1.6 : Bottom

1.7 : Perspective

1.8 : Perspective

The design is used as a front portion of a vehicle; the
portions colored with gray and black are the portions that are
claimed in the design product, the portions colored with dark
red and light red form no part of the claimed design; the
colors of the product are only used for showing the claimed
portions and disclaimed portions of the product, and the
design does not claim protection for a specific coloring;
design point of this design is the shape.
